UNITED STATES PATENT OFFICE.

EDGAR STEPHEN GEER, OF DIXBOROUGH, MICHIGAN.

DESIGN FOR A MEMBER FOR A COW-TAIL HOLDER.

SPECIFICATION forming part of Design No. 33,136, dated August 28, 1900.

Application filed July 9, 1900. Serial No. 23,056. Term of patent 14 years.

To all whom it may concern:

Be it known that I, EDGAR STEPHEN GEER, a citizen of the United States, residing at Dixborough, in the county of Washtenaw and State of Michigan, have invented and produced a new and original Design for a Member for a Cow-Tail Holder; and I do declare the following to be a full, clear, and exact description of the same.

10 My invention relates to a design for a member of a cow-tail holder, which is illustrated in the accompanying drawing, in which the figure is a perspective view.

15 My design consists of an arm *a*, having approximately an S-shaped curve, as illus-

trated, at one end, and at its opposite end the parallel and laterally-extending serrated flanges *b*.

Having thus described my design, what I desire to secure by Letters Patent is—
²⁰

The design for a member of a cow-tail holder, substantially as herein shown and described.

In testimony whereof I affix my signature in the presence of two witnesses.

EDGAR STEPHEN GEER.

Witnesses:

OLIVER A. AINSWORTH,
DARWIN C. GRIFFIN.
